JOSEPH CARROLL, OF BROOKLYN, NEW YORK, ASSIGNOR TO SPADONE MACHINE COMPANY, INC., OF NEW YORK, N. Y., A CORPORATION OF NEW YORK.

MACHINE FOR PRINTING, WINDING, AND PACKING.

Application filed April 26, 1927. Serial No. 186,647.

The invention relates more particularly to flexible materials or commodities in which the dimension of length is a prime factor, and which because of such factor and other inherent properties such as elasticity, are difficult to wind and pack, examples of such materials or commodities being found in steam and other packings, rubber hose, tubing and the like. The object of the invention is to provide a machine of simple construction whereby such materials and commodities may be easily wound and efficiently packed without the necessity for supervision by skilled operators. The invention contemplates further the provision of a printing mechanism of simple construction and reliable operation for marking the material or commodity prior to the winding and packing thereof. The invention will be fully described hereinafter and the features of novelty will be pointed out in the claims.

In the accompanying drawings, which illustrate an example of the invention without defining its limits, Fig. 1 is a sectional elevation of the machine; Fig. 2 is a plan view with parts broken away; Fig. 3 is a section on the line 3—3 of Fig. 1; Fig. 4 is a detail view of a detent included in the machine; Fig. 5 is a detail sectional elevation of the printing unit; Fig. 6 is a fragmentary section on the line 6—6 of Fig. 2; Fig. 7 is a fragmentary plan view of Fig. 6, and Fig. 8 is a detail section on the line 8—8 of Fig. 7.

For the purposes of illustration and description the invention is embodied in a machine for winding, packing and marking or printing packing of rectangular cross section and of the type commonly used for packing joints and for the manufacture of gaskets and the like.

As shown in the drawings, the machine comprises a supporting frame 10 of suitable form and dimensions including a cross-bar 11 on which the winding mechanism is mounted, said mechanism consisting of a vertical shaft 12, journalled so as to be vertically adjustable for the purposes to be more fully set forth hereinafter; the lower end of the shaft 12 preferably extends into and slidably fits a closed cylinder 13 which depends from the cross bar 11 as shown in Fig. 1. At its upper end the shaft 12 carries a plunger or piston 14, slidably fitted in an

upwardly open cylinder 15 comprising a depending continuation of a coiling receptacle 16; the latter is supported upon a table 17 carried by the frame 10, said table being provided with a suitable opening through which the cylinder 15 projects downwardly as illustrated in Fig. 1. A coiling reel 18 or equivalent device of any convenient form whereby the end of the packing A or equivalent commodity to be wound and packed, is temporarily and removably connected with the winding mechanism is mounted upon the plunger 14 either as an integral part thereof or as a separate element; in the illustrated example the reel 18 comprises a circular boss provided with a plurality of recesses 19 dimensioned and shaped to receive an end of the packing A or its equivalent with sufficient friction to hold it in place without interfering with its intentional removal at the proper time.

The coiling and packing mechanism further consists of a worm wheel 20 mounted on the shaft 12 and held against vertical movement by a bracket 21 fastened to the cross bar 11. The connection between the shaft 12 and the worm wheel 20 is such that the shaft is vertically adjustable relatively to said worm wheel but is coupled thereto so as to be rotated thereby; in the illustrated example the shaft 12 is accordingly provided with a key-slot 22 into which a key internally located on the worm wheel 20 slidably fits. The worm wheel 20 meshes with a worm 23 fixed upon a drive shaft 24 journalled in bearings 25 on the cross bar 11 and carrying a pulley 26 whereby said drive shaft 24 is connected with a source of power. Any suitable means may be provided for raising and lowering the shaft 12 to adjust the coiling reel 18 to and from an operative position in the receptacle 16 for the purpose to be more fully set forth hereinafter; for instance, as shown in the drawing a treadle 27 connected by means of a link 28 with a rocking lever 29 pivoted at 30 upon a bracket 31 projecting upwardly from the cross-bar 11 may be provided for this purpose, said lever 29 having a forked end pivotally connected with a collar 32 fixed upon the shaft 11 as illustrated in Fig. 3. In order to fix 100 105 the vertical adjustment of said coiling reel 18 to meet any particular requirements, a latch 33 is arranged to automatically engage

the treadle 27 and hold it in its depressed position; to permit the adjustment to be varied at will, the latch 33 is pivoted on a block 34 which is adjustably mounted on a stationary bracket 35 and is secured in an adjusted position by means of a set screw 35^a, as shown in Fig. 4. With this arrangement the position of the latch 33 will predetermine the depressed position in which 10 the treadle 27 is held and accordingly will predetermine the extent to which the reel 18 is projected upwardly into the receptacle 16. A spring 36 is provided for yieldingly forcing the latch 33 toward the treadle 33 so 15 that its engagement with said latch will be automatic, suitable provision being made to arrest the movement of said latch in a proper co-operative position when the treadle is out of engagement therewith.

20 In addition to the parts so far described, the winding and packing mechanism includes a retaining device 37 in the form of a circular cover or disc arranged to fit into the receptacle 16 and rest upon the reel 18 as shown in Fig. 1. To permit the device 37 to be easily manipulated relatively to the receptacle 16 as may be required, said device is suspended in axial registry with said receptacle by means of a rod 38 vertically 25 a shaft 68 in rolling contact with the printing member 62, said shaft 68 being journalled in the sub-frame 64, with the transfer roll 67 in rolling contact with an inking roll 69; the latter is carried by a shaft 70 beneath the outlet 71 of an ink receptacle 72 from which ink is delivered in a predetermined manner to the inking roll 69. In order that the entire surface of the roller 69 may be made available for transferring ink to the transfer roll 67, the shaft 70 in addition to being rotatable, is slidably mounted in the sub-frame 64 and is moved in one direction by means of a rocking arm 73 and a cam 74 mounted upon the shaft 63 and in the opposite direction by a spring 75, as shown in Fig. 5. In the preferred arrangement, a pressure roller 76 is arranged to force the packing A or its equivalent into engagement with the printing member 62, as illustrated in Fig. 1. This roller 76 is mounted upon a rocking lever 77 pivoted at 78 upon the table 11 and controlled by a spring 79 in a manner to at all times urge the roller 76 toward the printing member 62.

The machine preferably also includes guide rollers 80 carried by slotted plates 81, arranged to be fixed in adjusted positions by thumb screws 83, said rollers being located in registry with an opening 84 in the wall of the receptacle 16, as shown in Fig. 2. If desired, the machine may include flanges 85 adjustably mounted on a shaft 86 which, as shown, may be journalled in proximity to the printing member 62, the strip A in such case passing between said flanges 85 in its travel to the rollers 80 and the receptacle 16; the flanges 85 are adjustable to accommodate packing strips A of different dimensions or other articles which may be passed through the machine.

In describing the operation of the machine, the illustrated example thereof will be utilized, it being understood that this is not intended to define the limits of the invention; it is further to be understood that the packing A is intended to exemplify other commodities which fall within the field of usefulness of said machine. Generally speaking, the machine is adjusted to print, wind and pack successive articles of the same kind, this being done to provide a maximum of efficiency, although said machine may be used to successively operate on articles of varying physical characteristics, such as dimensions, cross-sectional form and the like, and in such case may be adjusted as often as necessary to meet the requirements of such articles. Assuming that the machine is to be utilized for marking or printing, winding and packing a length or strip of the packing A, which is of rectangular cross-section, the treadle 27 is depressed to raise the shaft 12 and to cause the reel 18 to project into the receptacle 16 to an

extent corresponding with the vertical thickness of the packing A as indicated in Fig. 1. The block 34 is then adjusted to set the latch 33 in a position in which it will hold the treadle 27 at the proper degree of depression to fix the reel 18 in such position at will and to automatically return it thereto each time the treadle is operated subsequently to a release of the parts as will appear more fully hereinafter. The one end of the strip of packing A is then passed between the rolls 46 and 47, the latter having previously been or being then adjusted relatively to the roller 46 to properly engage said strip A. Power is then applied to rotate the shaft 24, and the treadle 56 is depressed to throw in the clutch 55 and thereby couple the pulley 50 to said shaft 24. This will result in a rotation of the roll 46, through the medium of the pulleys 50 and 48 and the belt 49, and consequently will feed the strip A in a direction toward the receptacle 16, so that said strip A will pass between the flanges 65 and 85 and finally will pass between the rollers 80 and through the opening 84 into the receptacle 16. As soon as the strip A has passed into said receptacle 16 to the extent necessary to permit the same, the aforesaid end of said strip A is inserted into which ever one of the recesses 19 of the reel 18 happens to be in registry with or nearest to the opening 84; preferably the strip A is extended far enough into said receptacle 16 so that the end of said strip extends also into that recess 19 which is in opposed diametric registry with the first mentioned recess, as indicated by dotted lines in Fig. 2. At this stage, the strip A is accordingly detachably connected with the reel 18 and either immediately or at the predetermined interval of time thereafter, the clutch 55 is released so that the roller 46 is no longer driven positively, and from this point onward becomes merely an idler the same as the roller 47. At the proper time, subsequent to the completion of the connection of the strip A with the reel 18, the retaining device or disk 37 is lowered to the position shown in Fig. 1, in which it closes the receptacle 16 and with the latter defines a circular coiling channel having the opening 84 as an entrance. As the operation of the machine continues, the reel 18 will be rotated on its axis and the strip A will be drawn between the rolls 46 and 47 and through the opening 84 into the receptacle 16, to which it is guided by the idler rolls 80. The rotation of the reel 8 will at the same time progressively wind the packing A upon said reel and upon itself in the form of a coiled unit as will be clear from Fig. 2.

When the complete strip of packing A has been drawn into the receptacle 16 and coiled upon itself thereon, the latch 33 is shifted,

against the tension of the spring 36, to a temporary inoperative position to release the treadle 27 and thereby permit the plunger 14 and with it the reel 18 to drop, by gravity, to the inoperative position shown in Fig. 6; as this dropping movement of the reel 18 takes place, the corresponding downward movement of the shaft will be cushioned by the air in the cylinder 15 beneath the piston 14, and in the cylinder 13 beneath the shaft 12. The aforesaid downward movement of the reel 18 will cause the end of the strip A to be automatically forced out of the recesses 19 by the action of the bottom of the receptacle 16, said end as soon as it is released from said recesses, flexing into place at the inside of the coil because of the inherent elasticity of the strip A. When this condition is reached the slide b with the end of the cord a or its equivalent fastened in the notch d thereof is shifted inwardly beneath the coiled strip A through the medium of the rod e to the position indicated in Fig. 6. As the free end of the slide b passes inwardly beyond the coiled strip A, said free end, because of the inherent elasticity of the slide b, will automatically flex upwardly to the position indicated in Fig. 6, in which the attached end of the cord a or its equivalent is easily accessible, it being understood that, either at this stage or previously, the disk 37 has been shifted out of the receptacle 16, for instance, to the position shown by dotted lines in Fig. 1. The end of the cord a or its equivalent is then detached from the slide b and the cord or equivalent tying medium is then manually drawn through until a sufficient length is provided to completely pass around the coiled strip A and to enable said cord or its equivalent to be secured in place; the cord a or its equivalent is then cut at a convenient point and the two ends thereof are tied and knotted together or otherwise fastened in place to positively fix the strip A in the form of a coiled package. The application of the cord a or equivalent tying medium preferably takes place in proximity to the point at which the outer end of the strip A is located in the coiled package, so that uncoiling of the strip is prevented and an easily handled and convenient package is provided; if desired, additional lengths of cord a or its equivalent may be applied at different points of the coil in the indicated manner by simply rotating the receptacle 16 to bring the different points of the coiled package into registry with the slide b and its associated elements. When the tying operation has been completed the package of packing A or equivalent article or commodity is lifted from the receptacle 16 for storage, shipment and sale, or for subsequent treatment, as the case may be.

In its travel to the receptacle 16 the strip A or its equivalent, passes beneath and in contact with the printing member or wheel 62 in frictional surface contact therewith, and is maintained in proper registry with said printing member 62 by the flanges 68 on the shaft 63. The printing member 62 will accordingly be rotated and will produce impressions of whatever characters, symbols or other matter is contained upon its periphery, upon the contacting surface of the strip A; in this way the strip is marked, for instance, at spaced intervals with a trade mark or other trade device, or is otherwise marked as may be desired. The distance between the printing mechanism and the coiling means is such that whatever impressions are produced upon the strip A are dry or at least smudge proof before the actual coiling or winding operation takes place.

The machine is simple in construction and operation and is capable, without the necessity for skilled supervision, of efficiently marking, winding or coiling and packing materials in which the dimension of length is a prime factor and which, because of inherent properties, such as elasticity, are difficult to handle and pack. Such materials are exemplified by the packing strip A of the illustrated example, and by rubber hose and tubing, band springs and similar articles and commodities.

Various changes in the specific form shown and described may be made within the scope of the claims without departing from the spirit of the invention.

I claim:

1. A machine of the kind described comprising mechanism for coiling a strip of material upon itself, printing mechanism whereby said strip is marked prior to being coiled, and means whereby a tying medium is shifted into tying relation to the coiled strip.

2. A machine of the kind described comprising mechanism for coiling a strip of material upon itself, said mechanism including a coiling receptacle, means for guiding a travelling strip of material to said receptacle, printing means for marking said strip of material prior to the coiling thereof, said printing means co-operating with said guiding means to maintain said strip in its path of travel, and means whereby a tying medium is shifted into tying relation to the coiled strip.

3. A machine of the kind described comprising a support, a coiling receptacle carried thereby, a coiling reel for coiling a strip of material upon itself in said receptacle, driving means for operating said reel, and means whereby said driving means is adjusted to shift said reel into and out of its operative position in said receptacle, and

printing means whereby said strip of material is marked in its passage to said receptacle.

4. In a machine of the kind described, the combination of means for coiling a strip of material upon itself, a rotatable printing wheel for marking said strip prior to the coiling thereof, an inking roll, a transfer

roll in contact with said inking roll and printing wheel, and means whereby said inking roll is axially shifted relatively to said transfer roll.

In testimony whereof I have hereunto set my hand.

JOSEPH CARROLL.
